UNITED STATES PATENT OFFICE.

HUGO J. BAUR, OF CHICAGO, ILLINOIS, ASSIGNOR TO JAY M. JOHNSON, OF CHICAGO, ILLINOIS.

TOTAL-REGISTERING MEANS FOR COIN-RECEIVING PREPAYMENT DEVICES.

1,190,368.

Specification of Letters Patent. Patented July 11, 1916.

Application filed August 19, 1912. Serial No. 715,749.

To all whom it may concern:

Be it known that I, HUGO J. BAUR, a citizen of the United States, and a resident of the city of Chicago, in the county of Cook and State of Illinois, have invented certain new and useful Improvements in Total-Registering Means for Coin-Receiving Prepayment Devices; and I do hereby declare that the following is a full, clear, and exact description of the same, reference being had to the accompanying drawings, and to the numbers of reference marked thereon, which form a part of this specification.

This invention relates to improvements in fare registers of that class set forth in my co-pending application for patent for "total adding fare registers", filed Apr. 22, 1912, Serial No. 692,225, and in which the driving and controlling mechanisms for the register or veeder are secured axially upon the same shaft with a carrying element, so that they rotate upon the same axis therewith.

The object of this invention is to afford a construction wherein driving means for the register are mounted independently from the carrying element, thus rendering the same somewhat more accessible for inspection.

It is also an object of the invention to afford a construction wherein the carrying element which affords the floor for the receiving hopper, impels the coin one by one against shifting means to bring the register into train for registering said coin and to hold said mechanisms in train until the registering of the coin is effected and thereafter to immediately release the same.

The invention (in a preferred form) is illustrated in the drawings, and is herein-after more fully described.

In the drawings: Figure 1 is a central, vertical section, partly broken away, illustrating a fare register embodying my invention, and showing the same mounted in a fare box. Fig. 2 is an enlarged front elevation of the inclined frame and rotative carrying element with the hopper and discharge chutes removed. Fig. 3 is a rear elevation of the frame plate and driving means, with parts removed and in section. Fig. 4 is a section on line 4—4 of Fig. 2. Fig. 5 is a fragmentary section on line 5—5 of Fig. 2. Fig. 6 is an enlarged section on line 6—6 of Fig. 3, with parts omitted. Fig. 7 is a section on line 7—7 of Fig. 3, with parts omit-

ted. Fig. 8 is an enlarged top plan view of the mutilated pinion. Fig. 9 is a section on line 9—9 of Fig. 3, showing the parts at normal or out of train. Fig. 10 is a similar view, showing the parts in train.

60

As shown in the drawings: 1, indicates the fare box having a coin receptacle mounted thereon and containing a drawer or receptacle 3, to receive the coins after the same have been registered. Secured in said fare box are upwardly directed frame plates 4, having the front edge thereof bent upwardly and rearwardly at an angle, and supported thereon in inclined position is a front inclined frame plate 5. Secured between the vertical frame plates 4, and spaced a distance from the inclined frame plate 5, and parallel with the latter, is a similar inclined frame plate 6.

70

Journaled in the vertical frame plates 4, transversely the fare box, is a shaft 7, adapted to be rotated by a crank or other suitable means, and rigidly secured on which is a bevel pinion 8, which meshes with a bevel gear 9, rigidly secured on a shaft 10, journaled in a sleeve 11, secured on the rear inclined frame plate 6, as shown in Fig. 4. The outer end of the shaft 10, extends through, and is journaled in the front inclined frame plate 5, and rigidly secured on the outer end of said shaft and lying flat against said front frame plate, is a circular coin carrying wheel or element 12.

80

Rigidly (but removably) secured on the front inclined frame plate 5, and inclosing said inclined carrying element 12, and fitting closely around the periphery thereof, is a casing 13, having an opening in the top thereof indicated by A, through which the coins from the fare collecting box eventually fall by gravity. Said coin carrying plate or disk element 12, is provided on the face thereof, with upstanding outer projections 14, inclined inwardly and rearwardly from their front ends, as shown in Fig. 2, and as shown, arranged adjacent to, and slightly at the rear of corresponding projections 15, 16 and 17, arranged a distance from the periphery of the carrying element respectively equal to the diameter of the respective coin which it is purposed to collect and register in said device.

100

In the present instance, the machine is shown constructed for pennies, nickels and dimes.

110

dimes, and consequently the projections 15, are spaced from the periphery of the carrying wheel a distance approximately equal to the diameter of a dime, while the projections 16, are spaced from the periphery of the carrying wheel approximately the diameter of a penny and similarly, the projections 17, are spaced therefrom a distance approximately equal to the diameter of a nickel and the inner projections are spaced sufficiently in advance of the outer to permit a coin of less diameter than that for which said projections are intended to carry, to pass therebetween, so that each pair of said projections can carry but a coin of a predetermined diameter, and the inner projection is set a distance from the perimeter of the carrying wheel such that a smaller coin will pass therebetween while a coin of larger size will fall therefrom before reaching registering position at the top of the carrying wheel. As shown, a groove 18, is provided in the face of said carrying element concentric with the shaft 10, and extending between the projections of each pair and within the same and also concentric with the shaft, is an inner groove 19.

Rigidly secured on the shaft 10, beneath the inclined frame plate 5, is a gear wheel 20, and rigidly secured on a shaft 21, journaled in a bearing 22, therefor, is secured the gear 23 on the under side of the inclined frame plate 5, thereby affording a two to one drive. Also rigidly secured on said shaft 21, is a plate 24, shaped to afford a Geneva gear and the outwardly directed throws or stops of which are indicated by 25, 26 and 27 respectively. Rigidly secured on said shaft 21, and to the Geneva gear 24, is a mutilated gear 28, for actuating the registers. The carrying wheel is provided with two pairs of projections diametrically opposite from each other on said wheel for carrying pennies, two pairs of such projections also diametrically opposite each other for carrying dimes, and two other pairs similarly arranged, for carrying nickels. Inasmuch, however, as the relative sizes of the gears 20 and 21 afford a two to one drive, for the shaft 21, and the mechanism thereon as compared with the carrying wheel, it follows that but one group of teeth are provided on said mutilated gear for each of the respective denominations of coin the device is adapted to receive, and consequently a group of two teeth, indicated by 29, is provided on said wheel to register pennies, a group of ten teeth to register nickels, indicated by 30, and a group of twenty teeth to register dimes, indicated by 31, are provided thereon and spaced to afford substantially equal spaces between the groups. Also rigidly secured upon the shaft and through

said mutilated gear and Geneva gear, is a locking plate 32, which is shaped or formed to provide a downwardly directed, peripheral flange 33, integral with which and projecting outwardly from the lower end thereof are locking flanges 34, 35, and 36, arranged adjacent the penny, nickel and dime groups respectively, as shown in Fig. 3.

Secured upon a bracket 37, which is attached to the under side of the frame plate 5, is a veeder or register 38, provided with a bevel gear 39, as is usual, and journaled in a suitable bracket 40 in a suitable seat therefor, on the inclined frame plate 5, is a shaft 41, on the lower end of which is secured the bevel pinion 42, which meshes with the bevel pinion 39, on the register or veeder. Rigidly secured on said shaft 41, is a pinion 43, as shown, provided with eight teeth, and rotatably secured on said shaft above, and resting on the same, is a mutilated pinion 44, also having eight teeth, alternate teeth of which are of a length to engage, and do engage the mutilated gear and also the Geneva gear, while the remaining teeth are short and capable of meshing with the mutilated gear only.

The pinion 43, is secured on its shaft slightly below the mutilated gear, so that the same at all times is out of engagement therewith, but the rotative pinion 44, is at all times engaged with either the mutilated gear or Geneva gear or both, so that the veeder or register is normally out of train with the gear 23, which rotates continuously when the machine is in operation. Means are provided for bringing said veeder or register in train with said gear through the medium of said pinions and mutilated gear when a coin is brought to registering position upon the carrying wheel. For this purpose, as shown, upwardly directed parallel brackets 45, are provided on the inclined frame plate 5, and journaled therein is a shaft 46, near each end of which is secured outwardly projecting arms 47 and 48, the former of which extends over the top of the carrying wheel and is yoked at its extremity and has journaled therein a wheel 49, which tracks in the groove 18, in the carrying wheel, as shown in Figs. 2 and 4, so that as each coin is carried upwardly on the carrying wheel to registering position, the coin (by engagement beneath said wheel) causes the same to ride upwardly thereover. The other of said arms 48, as shown, is relatively longer than the arm 47, and pivotally engaged on the extremity thereof is a link 50, which extends through an aperture in the inclined frame plate 5, and inwardly substantially parallel the shaft 41. Secured on the inner end of said link is a yoke 51. A bracket 52, secured on the inclined plate 5, and, if desired, integral with the bracket 40, before described, extends beneath said yoke 139

- and extending therethrough and through suitable apertures in the arms of said yoke, and through a gear wheel 53, journaled between said yoke arms, is a shaft 54, the upper end of which is journaled in a suitable recess or seat therefor in the under side of the inclined frame plate 5. Said gear wheel meshes normally at all times with the pinion 43, rigidly secured on the veeder driving shaft 41, and is normally out of mesh with the rotative mutilated pinion 44, the latter of which is at all times in mesh with the mutilated gear and Geneva gear, so that when a coin passes beneath the arm 47, elevating the arm, the arm or lever 48, is thrown upwardly thereby, thus elevating the gear 53, by means of the link 50, to bring both said pinions into mesh therewith and thereby communicate the drive of the mutilated loose pinion 44, to the tight pinion 43, driving the veeder thereby. Of course, the amplitude of elevation of said gear for this purpose, need be but slight. Any desired elevation, however, may be attained by varying the relative length of the arms 47 and 48, or the depth of the groove 18, or both, so that even a very thin coin will afford sufficient shift for said gear wheel 43, to bring the veeder into train as before described.
- Means are provided for positively holding the mechanism in train until the money value of the coin has been recorded on the veeder. For this purpose, as shown, a bracket 55, is provided on the under side of the inclined frame plate 5, as shown in Figs. 2, 3, and 5, and journaled thereon at one end is an arm 56, which is relatively broad and strong, and may be constructed in the form of a channel or other structural form, if desired, and through the outer ends of the flanges of which extends a rod or stud 57, which, at its extremity, extends beneath the locking flanges or projections on the locking plate, as shown in Figs. 3 and 6.
- As shown in Fig. 7, a strong spring 58, is provided on the pintle for said arm and at one end engages the bracket, and at the other end engages over the arm and acts to hold the free end of the arm downwardly.
- As shown also, said arm at its extremity adjacent the mutilated gear and locking plate, is slotted, and engaged therein is a finger or projection 59, integral with the yoke 51, for the gear 53, so that when said gear is shifted upwardly, as shown in Fig. 10, to bring said pinions into mesh and drive the veeder, the free end of said arm 56, and the stud 57, thereon, are also shifted upwardly so that the end of the latter engages over the locking projection adjacent thereto and corresponding with the group of teeth on the mutilated gear in position next to actuate the register. In this position, said stud positively holds the register in train with the driving means, for example, a crank on the
- shaft 7, so that, entirely independently of the coin which first brought said elements into train, said mechanisms are positively held in train until the registering of the value of the coin is completed, when the stud is released from the locking projection on the locking plate, and the parts again thrust out of train by the action of the spring 58, and gravity.
- The operation will be evident from the foregoing description. It is, of course, to be understood that the relative proportions of the gears and pinions affording the driving train to the veeder, and the arrangement of the groups of teeth on the mutilated gear with reference to the pairs of carrying projections on the carrying plate or element, are such that the fraction of rotation of the pinions effected when the driving mechanism to the veeder is brought in train by a penny, shall be sufficient to record the proper money value, to-wit, one cent, upon the veeder, and similarly with other denominations of coins for which the machine may be constructed. It is evident that the carrying element performs no function whatever except to carry the coin into position to trip the shifting lever to bring the driving means entrain, and that the coin having tripped the shifting lever, performs no further function, the mechanisms being held in train until the completion of the registration by the mutual engagement of the revolving locking plate and the stud 57, which was elevated into such engagement simultaneously with the parts being brought in train to effect the drive.
- Of course, it is to be understood that details of construction may be varied through a wide range. I have merely illustrated and described but a preferred form of my invention. I therefore do not purpose limiting the patent to be granted on this application otherwise than necessitated by the prior art.
- I claim as my invention:
1. In a device of the class described a coin carrying element, means removed from the coin carrying element for driving a register, said means comprising in part gears mounted with their axes parallel to the axis of the coin carrying element, a register normally out of train with said driving means, shifting mechanism operated by contact with the surface of a passing coin to bring the register into train with its driving means, and means holding the register in train independent of the coin until the coin value has been registered on the register.
  2. In a device of the class described a coin carrying element, a register for the coin values, driving means normally out of train therewith and comprising in part gears mounted parallel to the axis of said coin car-

- rying element and disposed above the same, mechanism adapted to contact the surface of a coin and operated by each coin carried to deposit on said carrying element to bring the register into train with its driving means, and a detent acting to hold said register in train independent of the coin until the registration of the money value of said coin.
- 16 3. In a device of the class described an inclined rotative coin carrying element, different coin engaging means thereon, one for each denomination of coin to carry that coin only, a hopper for indiscriminately mixed 70 coins supported to discharge to said carrying element, means for driving the carrying element, a register for the coins, driving means for said register normally out of train with the register and comprising in 75 part gears mounted parallel to the axis of the carrying element and disposed above said axis of said coin carrying element, means operated by each passing coin for bringing the register in train with its driving means,
- 15 22 a detent acting to support said mechanisms in train until complete registration of the coin, and means immediately thereafter shifting said mechanism out of train.
- 23 4. In a device of the class described a continuously rotatable coin carrying element, driving mechanisms independent therefrom, and rotating simultaneously therewith, and disposed at the rear of and at a point above the axis of said coin carrying element, a register normally out of train with the driving mechanism, pivotally supported means for entraining the register with said driving mechanism, comprising a shifting lever extending over the carrying element in position to be held elevated by each passing coin, and means acting to maintain the register in train until complete registration of the coin and to release the register from said driving mechanism thereafter.
- 24 40 5. In a machine of the class described an inclined rotative coin carrying wheel, coin carrying projections thereon, said coin carrying wheel having a groove in the face thereof concentric therewith and lying between the coin carrying projections, a tripping lever extending over the faces of said wheel, a roller thereon extending into the groove and adapted to ride over each coin carried therewith on said carrying element, a shifting arm connected with said lever, a register, driving means therefor normally out of train therewith mounted at the rear of said carrying wheel at a point above the axis thereof, means connected with the shifting arm to bring the same into train when the tripping lever is elevated by each coin, and means holding the register in train until registration of the coin is effected.
- 25 45 6. In a device of the class described a rotative coin carrying element, means for driving the same, a register, rotative driving means for the register normally out of train therewith and disposed at the rear of said coin carrying element and at a point 70 above the axis of rotation thereof, means driving said driving means simultaneously with the coin carrying element, a lever disposed above the coin carrying element in position to be engaged and lifted by each passing coin, a shifting lever of greater length rigidly connected therewith and operatively connected to bring the register into train with its driving means when the tripping lever is elevated by a coin, and coacting means for holding the register in train independent of the coin until the coin value is registered.
- 26 7. In a device of the class described a hopper, an inclined rotative coin carrying 85 plate extending thereinto and affording a part of the bottom thereof, projections on said coin carrying plate adapted to selectively engage and carry indiscriminately mixed coins from the hopper one by one to 90 a place of deposit, a shifting lever extending into the path of the coins, a register, driving means therefor mounted at the rear of said carrying plate and at a point above the axis thereof and driven simultaneously 95 therewith, and normally out of train with the register, operative connections for bringing the register in train with its driving means when the tripping arm is elevated by a coin, and coacting detents acting to hold 100 the same in train until the coin value is registered.
- 27 8. In a device of the class described a rotative coin carrying element, a register, driving means independently mounted at 105 the rear of said element at a point above the axis thereof and driven therefrom, a register adapted to be driven thereby and normally out of train therewith, swingingly supported shifting mechanisms acting to 110 bring the register into train with its driving means when actuated by a passing coin, and means independent from the coins for holding the register in train until registration is complete.
- 28 9. In a machine of the class described a rotatable driving shaft, an inclined coin carrying wheel mounted thereon, a register driving shaft mounted at a distance from said driving shaft aforesaid, operative connections between said shafts for driving the same simultaneously, a register, means on the register driving shaft for driving the register and normally out of train therewith, a lever extending above the coin carrying wheel to be held elevated successively by each coin advanced thereby, shifting means connected with said lever for entraining the register with its driving means, and means independent of the coin for holding 115
- 29 10 120 125 130

the same in train until the coin is registered.

10. In a device of the class described a flat inclined coin carrying element, a plurality of different means thereon adapted to engage coins of different denomination, a register to register the coins in accordance with the denomination thereof, a drive for said register disposed at the rear of said carrying element and at a point above the axis thereof, and means entraining the register with said drive by contact with the surface of a coin on said carrying element.

11. In a device of the class described a coin carrying element, a register for registering the coins, driving means for said carrying element, driving means for said register removed from said first mentioned driving means and operatively connected therewith to be driven thereby, and means actuated by contact with the surface of a coin on the element to entrain said registering mechanism with said register driving means to cause actuation of the register.

12. In a device of the class described means carrying a coin, a register, mechanism for properly actuating the register in accordance with the denomination of the coin advanced on said carrying means, said mechanism disposed at the rear of said carrying means and at a point above the axis thereof, and a pivotal shifting mechanism actuated by contact with the surface of a coin on said carrying means to entrain said register mechanism to register the coin.

13. In a device of the class described a coin carrying element, a register for the coin, gearing to drive the register in accordance with the denomination of coin carried on said element, said gearing disposed at the rear of said carrying element and at a point removed from the axis of rotation thereof, driving means connected to said carrying element for driving said gear, and pivotal means engaging a groove on said carrying element adapted to be actuated by a coin thereon to entrain said register with said register gear to register the coin.

14. In a device of the class described an inclined coin carrying element, differently spaced projections thereon adapted to engage coins of different denomination, a register, driving mechanism therefor oper-

tively connected with said carrying element to move coincidently therewith whereby the proper actuating mechanism for a coin of particular denomination is in position for register when certain of said projections on said carrying element are in a certain position, said driving mechanism disposed at the rear of and at a point above the axis of rotation of said carrying element, and means adapted to contact the coin carried by a projection on said carrying element to entrain the register with said registering actuating mechanism to properly register the coin carried.

15. In a device of the class described an inclined coin carrying element, means for driving the same, a register, actuating mechanism for said register, said actuating mechanism disposed at the rear of and mounted above the axis of rotation of said carrying element, driving connections between said coin carrying element and said register actuating mechanism, a pivoted arm mounted adjacent said coin carrying element adapted to contact coins thereon, another arm connected thereto, and a sliding gear actuatable by said latter arm to entrain the register with the register actuating mechanism to register a coin passing on said element.

16. In a device of the class described a coin carrying element, a register, register actuating mechanism comprising in part gears mounted parallel to the axis of said carrying element and removed therefrom, operative connections between said register actuating mechanism and said carrying element, a loose gear connected to be continuously driven by said register actuating mechanism, a tight gear connected to actuate the register mounted adjacent thereto, and means actuatable by a coin on said carrying element to lock said tight and loose gear together to cause actuation of the register by said actuating mechanism to properly register a coin on said element.

In testimony whereof I have hereunto subscribed my name in the presence of two subscribing witnesses.

HUGO J. BAUR.
